L. WOLFFGRAM.

TUBE, PIPE, AND ROD DRAWING APPARATUS.

APPLICATION FILED MAY 2, 1919.

1,322,858.

Patented Nov. 25, 1919.

INVENTOR.

Ludwig Wolffgram,

BY C. P. Geiger

ATTORNEY.

UNITED STATES PATENT OFFICE.

LUDWIG WOLFFGRAM, OF ERIE, PENNSYLVANIA.

TUBE, PIPE, AND ROD DRAWING APPARATUS.

1,322,858.

Specification of Letters Patent. Patented Nov. 25, 1919.

Application filed May 2, 1919. Serial No. 294,241.

To all whom it may concern:

Be it known that I, LUDWIG WOLFFGRAM, a citizen of the German Empire, and resident of Erie, county of Erie, and State of Pennsylvania, have invented certain new and useful Improvements in Tube, Pipe, and Rod Drawing Apparatus, of which the following is a specification.

The present invention relates to tube and pipe drawing apparatus, and has for an object to provide improvements in the means for drawing the tubes, pipes or rods, by which after the tube, pipe or rod has been drawn through the forming dies, the movable drawing carriage will automatically (by gravity in the present disclosure) return to its first position. Heretofore, it has been necessary to return the carriage to its first position by hand or by some mechanical and power consuming means. In the present invention, I propose to provide means which will utilize the force of gravity to return the carriage to its first position, and to this end I provide in the present embodiment an inclined platform or guide along which the carriage is drawn upwardly during the drawing of the tube, pipe or rod, the carriage moving by gravity when released to its first position.

With these and other objects in view, an embodiment of my invention is shown in the accompanying drawings, and this embodiment will be hereinafter more fully described with reference thereto, and the invention will be finally pointed out in the claims.

In the accompanying drawings:

Figure 1 is a diagrammatic side view of a pipe, tube or rod drawing apparatus embodying my invention; and

Figs. 2 and 3 are diagrammatic detail views of the carriage showing the two positions thereof, viz. with the jaws gripping the pipe, tube or rod, and with the same released by the jaws.

Similar reference characters indicate corresponding parts throughout the several figures of the drawings.

Referring to the drawings, the embodiment disclosed diagrammatically therein comprises a carriage 1, disposed upon a support or guide 2, inclined relatively to the horizontal floor, the angle of inclination being indicated by $\pi \alpha$. The carriage is provided with pivoted jaws 3 and 4 adapted upon turning of the cam 5 to the position

indicated in Fig. 2 to grip the end of the pipe, tube or rod, the said cam being movable with the pivoted lever 6 provided at one end with a weight 7 and at its other end with a hook 8. By turning the cam to the position indicated in Fig. 3, the jaws are released from the pipe, tube or rod, this operation being performed automatically as will hereinafter appear.

Extending along the guide 2, at one side of the die holder 9 in which are mounted suitable drawing dies and through which the pipe, tube or rod 10 is drawn, there is provided a chain 11 carried over sprocket gears 12 and 13 and adapted to be propelled in the direction of the arrow 14 by suitable gearing indicated by imaginary lines at 15, 16 and 17.

The hooked end 8 of the lever 6, carried by the carriage, is engaged with the chain and from the position indicated in full lines, Fig. 1, the carriage is drawn upwardly along the inclined guide 2, drawing the pipe, tube or rod through the drawing dies to the position indicated in dotted lines, Fig. 1, and as the carriage reaches this dotted line position, the pipe, tube or rod being fully withdrawn from the dies, the lever 6 engages a stop 18 causing the hooked end 8 to be disengaged from the chain and through operation of the cam 5, the pipe, tube or rod is released from the jaws, the weighted end of the lever preventing the hook from reengaging the chain. Upon removal of the pipe, tube or rod, the carriage moves by gravity along the inclined guide or support to its first position being limited at the end of its downward movement by means of a stop 19. The carriage may thereupon be engaged with the end of another length of pipe, tube or rod, and the drawing operation repeated.

With my improvements, a very simplified machine is provided, and the necessity of returning the carriage to its first position by hand or by mechanical means is entirely done away with.

I have illustrated and described a preferred and satisfactory embodiment of my invention, but it is obvious that changes may be made therein, within the spirit and scope thereof as defined in the appended claims.

I claim:

1. In an apparatus of the character described, an inclined support, a carriage disposed upon said support, means for propelling

2
ling said carriage upwardly along said support, said carriage adapted to move downwardly along said support by gravity.

2. In an apparatus of the character described, a forming die, an inclined support, a carriage disposed upon said support, means for propelling said carriage upwardly along said support to draw pipe, tubes, rods or the like through said die, 10 said carriage adapted to move downwardly along said support by gravity.

3. In an apparatus of the character described, an inclined support, a carriage dis-

posed upon said support, means for propelling said carriage upwardly along said support, means adapted to automatically disengage said carriage from said propelling means at the end of its upward traverse, said carriage adapted to move downwardly along said support by gravity upon being 20 released from said propelling means.

In testimony that I claim the foregoing as my invention I have signed my name hereunder.

LUDWIG WOLFFGRAM.
